UNITED STATES PATENT OFFICE.

ELISA MAGDALENE JOHNSON, OF BROOKLYN, NEW YORK.

CAR-FENDER.

SPECIFICATION forming part of Letters Patent No. 603,728, dated May 10, 1898.

Application filed September 9, 1897. Serial No. 651,040. (No model.)

To all whom it may concern:

Be it known that I, ELISA MAGDALENE JOHNSON, a citizen of the United States, residing at Brooklyn, in the county of Kings 5 and State of New York, have invented certain new and useful Improvements in Car-Fenders; and I do hereby declare the following to be a full, clear, and exact description of the invention, such as will enable others skilled 10 in the art to which it appertains to make and use the same.

This invention has reference to a novel construction in a car-fender, the object being to provide a device of this character that will 15 effectually prevent a person being run over by electric or other motor cars.

The invention consists in the features of construction hereinafter fully described and claimed.

20 In the accompanying drawings, forming a part of this specification, Figure 1 is a side elevation of the front end portion of a car provided with this fender. Fig. 2 is a vertical section through one side of the fender. 25 Fig. 3 is a perspective view of the fender detached.

Referring now to the drawings in detail my novel fender consists of a V-shaped frame having vertically-arranged sides and hooks 2222 30 at the rear side thereof for suspending it from the dashboard or front end of a car, said frame being preferably about five or six feet in height and of such a length as to give the desired angular structure to throw a person 35 or animal to one side of the track. This frame is constructed, preferably, of a single piece of metal, as shown in the drawings. The lower or base portion of this frame (indicated in general on the drawings by the number 40 3) is constructed as follows: The upper edge is turned inward and downward, so as to constitute a flange 6, having an angular relation to the outer or face portion 7. The lower edges of these two faces or flanges 6 and 7 are 45 then turned, respectively, outward and inward, so as to constitute a rigid base at 8 and to leave between them a groove adapted to support a strip of rubber 5, having an enlarged upper portion 9 for holding it in place. 50 This strengthened base 3, as thus described, runs entirely around the lower portion of the

fender, while the upper portion of the fender consists of a single rail, as shown, joined at its front or V-shaped end to the lower base by two vertical standards 11.

55

At the rear and bottom of the V-shaped fender are constructed two braces 11 11, formed by turning an extended portion of the metal from which the frame is constructed inward, as shown, so that their inner ends 60 rest, respectively, against the rear ends of the downwardly-turned flanges 6 6.

The numeral 4 represents a lacing of strong cord or of such elastic or yielding material as will not materially injure a person or animal 65 when struck, said lacing being secured in place between the top and bottom rails, the rear portion of the frame, and the vertical standards 11.

The operation of this novel fender will be 70 obvious, it being apparent that when secured to the dashboard of a car in the manner indicated it will act, by reason of its yielding vertically-arranged side walls, to throw a person sidewise from the track and therefore 75 avoid the danger of falling beneath the wheels thereof and also any danger of a damaging shock.

I am aware that heretofore a car-fender has 80 been devised of horseshoe or oblong shape in which the walls were so arranged as to lift a person or animal bodily from the track after the manner of the cow-catcher of a locomotive, as disclosed in United States patents to Bean, No. 509,646, dated November 28, 1893, 85 and McKinnon, No. 511,640, dated December 26, 1893, and also that it is old to provide a yielding network or lacing for car-fenders, as described and shown in the before-mentioned patent to McKinnon, and I make no claim here- 90 inafter broad enough to include such structures, my most generic claim being to a V-shaped car-fender with yielding vertically-arranged walls, whereby a person or animal is thrown laterally from the road-bed without 95 damaging shock and out of the way of the car.

Having thus described my invention, what I claim, and desire to secure by Letters Patent of the United States, is—

100 A car-fender of V shape having a rigid base of two flanges 6 and 7 which support a strip of rubber or other yielding material 5 beneath

them, in combination with vertically - arranged walls of lacing material, together with hooks for attaching the fender to a car and braces 11, 11 located in the rear of and near the base of the fender, substantially as described.

In testimony whereof I have signed this

specification in the presence of two subscribing witnesses.

ELISA MAGDALENE JOHNSON.
